UNITED STATES PATENT OFFICE.

CARMELO ATONNA, OF NEW YORK, N. Y.

ABDOMINAL BELT.

1,097,383.

Specification of Letters Patent.

Patented May 19, 1914.

Application filed September 30, 1912. Serial No. 723,164.

To all whom it may concern:

Be it known that I, CARMELO ATONNA, a subject of the King of Italy, and resident of the city of New York, in the county of New York and State of New York, have invented certain new and useful Improvements in Abdominal Belts, of which the following is a specification.

The present invention relates to abdominal belts or supporters, and has for one of its objects to provide a device of this type which can be readily adjusted to different forms and also abnormal conditions of the body, supporting the parts in an effective manner without inconvenience to the wearer.

Another object of the invention is to provide the abdominal belt with means to prevent the upward movement of the belt upon the body, such means being constructed in such a manner so as not to irritate or inconvenience the perineum or the exterior genital organs of the wearer.

A further object of the invention is to produce a belt with means which is adapted to support the abdominal walls in case of relaxation of the same or in another position to hold the inguinal hernia or hernias, and in both cases to protect at the same time the post-operative scar or scars which might be present in those parts of the body.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and minor details of construction within the scope of the appended claim without departing from the spirit or sacrificing any of the advantages of the invention.

One of the many possible embodiments of the invention is illustrated in the accompanying drawings, in which:—

Figure 1 is a front elevation of the belt stretched out flat; Fig. 2 shows the belt applied to the body of a wearer in front elevation; Fig. 3 in rear elevation; and Fig. 4 shows in front elevation positions of the parts differing somewhat from those shown in Fig. 2.

In the drawings, the numeral 10 represents the front of the support or belt, made,

preferably, of a flexible but non-elastic material, for instance leather, although it will be easily seen that a suitable fabric or a plurality of layers of fabric of the proper strength might just as well be used. This front is substantially trapeziform, the larger one of its two parallel sides forming the upper edge and the smaller one the lower edge of the belt. The formation of the front of the belt corresponds thus substantially to that of the anterior wall of the abdomen of the human body. At suitable intervals the front part 10 is provided with slots 11, the functions of which are to permit the front part to accommodate itself fully to the shape of the wall of the abdomen, and to provide at the same time a very effective ventilation which is very necessary in an article of this kind which is worn constantly. A plurality of stays 12, 12 are provided, the extreme ones of these stays being arranged at the inclined edges of the front 10 and the others between the same. To the front are attached triangular elastic sections 13 and 14, which are united with the back parts 15 and 16, respectively, said back parts being smaller in height than the front, whereby a belt is formed which decreases in height from the middle to its ends. The back parts 15 are also provided with longitudinal slots, denoted by the numerals 17, 17, for the same purpose as the slots in the front part. Stays 18, 18 of a suitable material are arranged upon the back parts 15 and 16, to give said back parts the required rigidity.

To the back part 15 are secured in any suitable manner two non-elastic straps 19, 19, preferably of web, of a suitable width and strength, the said straps meeting at 20 and being united with a single non-elastic strap 21, the end of which carries a buckle 22 of any suitable construction, which buckle is adapted to engage a non-elastic strap 23 which is fastened to the outer end of the back part 16. The inner end of the strap 23 is provided with a plurality of perforations 24, 24, which are adapted to engage a stud 25 upon the back part 15. Before the buckle 22 is engaged with the strap 23, the free end of the latter is passed through either one of two supporting loops 26 or 27, for a purpose hereinafter to be described. The supporting loops 26 and 27 are formed, preferably, by sewing transversely a strip of leather or tape to the central section of the belt.

In line with the inclined edges of the front part of the belt are attached to the latter elastic straps 28, 28, the free ends of which are provided with non-elastic portions 29, 29, the latter having button-holes 30, 30 adapted to engage buttons 31, 31, arranged near the lower portions of the front edges of the back parts of the belt.

The device is applied as follows: The belt 10 is placed about the body and one of the perforations 24 in the strap 23 engaged with the stud 25. The strap 23 is then passed through the aperture, formed between the non-elastic straps 19, and through either one 15 of the loops 26 and 27, to be engaged, after being drawn tight, with the buckle 22. If, for instance, the abdominal walls of the patient are relaxed and are to be supported, the strap 23 is drawn through the upper one 20 of the loops, that is the loop 26, and if on the other hand the inguinal hernia or hernias are to be held, the strap 23 is drawn through the lower loop, that is the loop 27. The belt 25 will, of course, at the same time in both cases protect the post-operative scar or scars, if there is or are any in these regions. The elastic straps 28, 28 are then applied to the legs of the wearer and their button-holes engaged with their buttons 31. It should be 30 observed that the strap 28, which is attached to the left-hand edge of the front part 10, is drawn around that leg of the wearer which is to some extent encircled by the elastic section 13 and the back part 15 of the belt, 35 and the other elastic strap around the other leg. Owing to the fact that these straps are arranged at an angle to each other, or in other words in line with the inclined edges of the front part, the said straps will in no 40 way inconvenience or irritate the perineum or the exterior genital organs of the wearer. As far as known, in all other belts heretofore used these straps run parallel to each other and cause thereby inconvenience to the 45 parts mentioned.

It should be noted that by making the front part 10 and the back parts 15 and 16

of leather, which, although flexible, is non-elastic, an efficient and well resisting abdominal support and compress is obtained. 50 By providing the slots in the front and back parts of the belt, the free passage of air is assured, the weight of the belt reduced and a fitting of the structure to the abdominal wall obtained. This, in combination with 55 the particular formation of the front part 10, will cause the latter to fit anatomically that section of the abdomen which is very easily weakened and which needs mostly support.

The sections 13 and 14 of the belt are made elastic to allow of free ambulatory movements of the wearer, and at the same time of a free movement of the flanks of 60 the trunk.

What I claim is:—

An abdominal belt comprising a substantially trapeziform front part, back parts and triangular elastic sections connecting said front and back parts, non-elastic straps attached to the ends of said back parts, means for detachably fastening together the ends of said straps, supporting loops for holding said straps in their proper positions, one of said straps being provided with a plurality of perforations, a stud upon one of said back parts adapted to be seated in one of said perforations for adjustably holding the ends of the back parts together, elastic straps fixedly attached in line with the inclined downwardly converging edges of said front part, and coacting means upon the free ends of said elastic straps and the front edges of said back parts for securing the said ends to said back parts, substantially as and 75 for the purpose specified.

Signed at New York, in the county of New York and State of New York, this 16th day of September, A. D. 1912.

CARMELO ATONNA.
